(57) **CLAIM**

The ornamental design for an automobile, as shown and described.

DESCRIPTION

FIG. 1 is a front view of an automobile showing my new design.

FIG. 2 is a rear view thereof.

FIG. 3 is a top plan view thereof.

FIG. 4 is a right side view thereof, the left side being a mirror image of the right side.

FIG. 5 is a front perspective view thereof; and,

FIG. 6 is a rear perspective view thereof.

The bottom view is omitted because it is devoid of any surface ornamentation.
